MOLD PLUG

John D. Dagenhard, Magnolia, Ohio, assignor to The Whitacre-Greer Fireproofing Company, Waynesburg, Ohio, a corporation of Ohio

Filed July 2, 1959, Ser. No. 824,702

3 Claims. (Cl. 22—148)

This invention relates to mold plugs for ingot molds and more particularly to an improvement in that class of mold plugs exemplified in the United States Whitacre Patent No. 2,798,268, issued July 9, 1957, by virtue of which each plug shall be so securely attached to the bottom of its respective ingot that it will, without substantial exception, be withdrawn from the mold entirely with its ingot without fracture and without sticking in whole or in part in the bottom hole in the mold.

Although the Whitacre patent greatly improved upon all prior practices and mold plugs for the objects and purposes stated therein, still there recurred, in my observation and experience, a small but significantly costly and aggravating persistence of failure in respect to whole or partial detachment of plugs from ingots and/or incomplete withdrawal from, or sticking in or fracture in the mold and/or providing an insufficient stool or support for the ingot when the ingot was taken from the mold and sought to be placed in a vertical position and supported by and upon an attached mold plug as a stool or elevating support therefor.

My study of this particular aspect of the problem, which was not entirely solved by the specific teaching of the Whitacre patent, led me to the discovery that the desired and intended casting of fins or projections in the slots of the plug was being impaired or prevented largely or entirely because air or other gases tended to be and sometimes actually was or were trapped or generated or in some way caused to be or remain in the slots, or bottom of the slot structure.

It is, therefore, an object of my invention to solve this problem to the extent it remained unsolved by the Whitacre plug and practice, and it is my more particular object to free the Whitacre plug from its possibilities of and tendencies toward trapping gases in the slots or in any way to impair the casting of the intended or sufficient steel fins therein to unfailingly attach every plug to every ingot. It is among my objects to aid in and improve upon the fulfillment of the objects of said Whitacre patent. It is also among the objects of my invention to prevent generated or occluded gases from impairing the casting of fins in the slots of the plugs to their full intended depth or to no less than the depth or completeness which is or could be desired for the full intended utility of every plug and its desired best unfailing and uniform attachment to the lower end of every ingot cast therewith.

Another object is to encourage the ingress of molten steel into the slots of the plug. A more specific object is to provide a vent from the slots, voids or fin-forming or projection-forming structure of mold plugs, of all the gases which might be trapped or be present therein with deleterious effect against the desired attachment between plugs and ingots, and however, to prevent deleterious or wasteful loss of steel through or from such a vent.

In pursuit of these objects of my invention, I found that a centrally located vent hole formed in the middle bottom of the slot structure of the plug and of relatively small size serves to guarantee the exhaustion of all gases "in front of" and below the downward flow of steel into the slots upon the first pourings of steel at the beginning of the pouring of the ingot. This appears to be especially the case when the slot structure is mouthed or beveled upwardly and outwardly at the top of the plug to invite the

2

ingress of fluid steel into the slot structure. Such a vent hole is preferably made big enough so that it will not be closed inadvertently in the course of manufacture or handling the wet clay plug before it is fired, and still made small enough to prevent any substantial or deleterious outflow of steel therethrough. In my preferred practice some molten or viscous steel enters the vent hole to insure, or be the sign of, evacuation of gases from the slot structure. Then preferably the steel freezes in the hole before filling it or flowing to any deleterious extent therethrough.

It was my observation that the Whitacre patented plugs, lacking merely my herein improvements, were successful in the respect discussed herein in about 90% to 99% of the instances of their use, but the same plugs altered only by the incorporation of my improvements have, as far as my present experience and observation have been able to confirm, been entirely successful in these respects, i.e., in their whole, unbroken and unfailing attachment to and "integration" with the bottom end of the mold and their unbroken withdrawal from the mold with the ingot without deleterious injury to the plug.

These and other objects and advantages of my invention will more fully and at large appear from the following description of preferred forms thereof, reference being had to the accompanying drawings in which:

FIGURE 1 is a top plan view of a mold plug embodying my invention;

FIGURE 2 is a vertical, longitudinal section of the plug shown in FIGURE 1 taken in the plane of the line 30 2—2 thereof;

FIGURE 3 is a longitudinal fragmentary sectional view on a reduced scale showing the lower part of an ingot mold with an ingot cast therein and engaging my improved plug; and

FIGURE 4 is a top plan view of an illustrative modified form of mold plug embodying my improvement.

The mold plug P is preferably made of ceramic material such as fire clay and otherwise as taught in the Whitacre patent, and takes the form of a truncated cone adapted to fit into the tapered hole H, FIG. 3, in the bottom of the ingot mold M to close the same against the egress of molten steel as is understood in the art and more fully explained in the Whitacre patent. The plug in its truncated form has a flat circular upper face 21 and a flat circular lower face 23 and is characterized by narrow intersecting slots 25 which open into the upper face 21 of the plug and extend downwardly into the body of the plug about two-thirds or three-quarters of the whole depth thereof to their bottoms 26. Preferably the slots in this form have enlarged ends 26, and, improving and departing from the specific teachings of the Whitacre patent, I prefer that the upper ends of the slotted structure be flared outwardly as at 27 to invite the more ready reception and intake of molten steel into the intersecting slots or slotted structure 25.

To assure the egress of air and gas from the whole slotted structure when the hot steel is poured into the mold and flows into the slotted structure 25, I provide in the middle of the bottom of the plug, the vent hole 30 out of which air and gas may escape at the bottom of the slotted structure when the steel flows into the slots at the top thereof. As suggested in FIGURE 3 in the preferred practice of my invention, the size of the hole 30 is large enough to exhaust quickly all the gases from the slotted structure 25 and small enough to inhibit the substantial outflow of steel through the hole 30 before the steel freezes therein. In a preferred functioning of my invention a small tip 31 of steel will penetrate the hole perhaps half of its length before it freezes or becomes too viscous to flow any further; this, as I observed, insuring that the gases will have been exhausted out of slot structure ahead

of steel flowing thereinto and insuring the casting of the steel fins therein according to the intention and objects of the Whitacre patent. In FIGURE 3 the section is taken through fins F lying transversely of the plug and integrally connected with the body of the ingot above and with the tip 31 in the vent hole 30 below. As taught and intended in the Whitacre patent a well formed fin structure F, of which the slot structure 25 is the matrix, should satisfactorily and securely attach every plug to every ingot. Now my improvement provides and insures this desired and desirable result.

For a specific example of a preferred form of my invention, the plug of FIGS. 1-3 may be 4" deep, 7" maximum diameter and 6" minimum diameter with the slots 25 intersecting in the central vertical axis of the plug and symmetrically disposed and having an overall width, i.e., maximum horizontal dimension, FIGS. 1 and 3, of about 3" to 4", a thickness (corresponding to fin thickness) throughout the rectangular portions of about $\frac{1}{8}$ " to about $\frac{3}{16}$ ", and the slots having enlarged cylindrical terminal ends 26 struck on about a $\frac{1}{8}$ " to $\frac{1}{4}$ " radius and symmetrically disposed in relation to the intervening straight rectangular parts of the slots. In this form I prefer that the slots have a depth of 3" to $3\frac{1}{2}$ ". In such a plug I prefer to make the vent hole about $\frac{1}{4}$ " in diameter when it is as short as about $\frac{1}{2}$ " in length and not greater than about $\frac{1}{2}$ " in diameter if the hole is to be as much as about 1" long. It may also be kept in mind that since the main function of the vent hole is to permit the outflow of gas, my purpose is merely to have the hole large enough to assure a free rapid outflow of gas at the moment of casting the fins, and any making of the hole larger than this necessary minimum is merely to preserve an adequate orifice against the hazard of the partial closing thereof as by wiping over or squeezing the bottom end of it while the clay of the plug is wet and/or being worked, dried or fired.

In the operation of my invention the first rush of molten steel to the bottom of the mold strikes, washes over or floods over the upper surface of the plug tending to flow into the slot structure 25 and being directed and guided into the slots by the beveled and chamfered upper openings 27 thereof whereupon to flow downwardly into and fill the slots with present new freedom and certainty by virtue of the free egress of the air and gases through the vent hole 30. As presently informed, I believe that the manner in which the molten steel flows into the slotted structure of my improved plug is probably different from its manner of flow into any prior plug by virtue of its speed and fluidity. According to prior practice, as I believe, air and gases trapped in the slot structure tended to prevent the full casting of the desired fins therein, not merely by gas displacing steel, but rather by slowing the flow of steel in the slots sufficiently to let it lose heat rapidly and gain viscosity and tend to freeze before filling the slots, and, possibly, before greatly compressing the trapped air or gases. The rapid filling of the slots with hot fluid steel permits the advantageous employment of narrower slots and a thinner fin structure while still gaining my better attachment of the plug to the ingot. The smallness of my vent hole and the relative length thereof will transfer heat quickly to the plug structure adjacent the vent hole and preferably freeze the steel before it fills the whole depth of the hole. Thereupon the whole fin structure will have been poured, and the casting thereof in the slot structure of the plug will be well initiated wherewith to guarantee the desired successful attachment to and coaction between the plug and the ingot.

The environment of my invention in FIGURE 4 is that of a plug P' the same as the plug P having, however, an-

other form of slot structure 35 as also suggested in the Whitacre patent and for the purposes thereof with, however, my same vent hole 30 located in relatively the same place to do the same work in the same way and get the same results as in the slot structure 25 of FIGURES 1-3. In the form of FIGURE 4 the upper open ends of the slots 35 may be beveled and outwardly chamfered as at 37 corresponding to the similar construction 27. As taught in the Whitacre patent the curved slotted structure 35 of FIGURE 4 may do much the same work in a somewhat different way compared with the straight slotted structure 25 and get about the same results. The slots 35 have preferably the same proportions and occupy about the same space in the plug as taught in respect to FIGURES 1 and 2, and for the same reasons. The mode of operation and advantages of my improvement in its environment of FIGURE 4 will be substantially and essentially the same as that described above with respect to FIGURES 1-3.

Other changes, modifications, adaptations and environments in, of and for my invention and improvement will occur to those skilled in the art who come to appreciate and understand the same. And I do not care to be limited in the scope and effect of my patent to the preferred forms and embodiments of my invention herein specifically illustrated and described, nor limited in any manner inconsistent with the progress by which my invention has promoted the art.

I claim:

1. In the combination of a big-end-up ingot mold and a plug for the lower opening thereof, an improved plug closing the lower opening of said ingot mold whilst the ingot is being cast and being disposed to become attached to the ingot during the casting thereof, said improved plug having spaced upper and lower faces and having a voided portion opening through the upper face whereby to be receptive of fluid ingot material from the bottom of the ingot tending to attach the plug to the ingot and having a vent leading downwardly away from said voided portion and through which gas but not ingot material may escape to atmosphere when said fluid ingot material enters said voided portion whereby to tend to assure the filling of said voided portion with ingot material.
2. In the combination of claim 1 wherein said vent in said improved plug comprises a hole opening through said lower face and of length and diameter tending to freeze fluid ingot material therein.
3. In the combination of claim 1 wherein the said inner voided portion of said improved plug comprises wide, thin slots with flared upper openings receptive of molten ingot material, and said vent comprises a hole leading from the bottom of said slots through the bottom of said plug and proportioned to permit gas to escape therethrough and cause ingot material to freeze therein.
